UNITED STATES PATENT OFFICE.

LEWIS A. DARLING, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

SPEED-GOVERNOR FOR ENGINES OR MOTOR DEVICES.

1,401,320.

Specification of Letters Patent. Patented Dec. 27, 1921.

Application filed March 27, 1918. Serial No. 225,016.

To all whom it may concern:

Be it known that I, LEWIS A. DARLING, a citizen of the United States, residing in the city and county of Philadelphia and State 5 of Pennsylvania, have invented certain new and useful Improvements in Speed-Governors or Engines or Motor Devices, whereof the following is a specification, reference being had to the accompanying drawings.

10 The invention is particularly applicable to engines actuated by steam or other elastic fluid, but is not restricted thereto.

An object of the invention is to provide a governor having automatic means responsive to the speed of the engine for controlling the supply of motive medium, in combination with means or devices also controlled by the speed governor for applying a brake-load of varying intensity, provided 15 the speed of the motor exceeds a predetermined point, through defective control of the motive medium by said governor, or from other causes.

In the drawings, which show by way of 20 illustration one embodiment of the invention, Figure I, is a view, partly in side elevation and partly in axial section, showing a turbine generator embodying my improvements.

25 Fig. II, is an enlarged detail view partly in similar section and partly in side elevation showing the automatic governor and the devices associated therewith, the governor element and connections being represented as in a different working position 30 from that indicated in Fig. I.

Fig. III, is a view similar to that of Fig. II, showing the parts in a further changed position, *i. e.*, that which corresponds with 40 the application of a friction brake-load to the turbine.

Fig. IV, is a detail view showing the throttle valve with the steam ports wide open.

45 I have embodied my invention in a turbine generator which is especially designed for use in steam locomotive electric headlight service. It is extremely important in devices of this character to obtain a close 50 and steady control under wide changes of load and also wide changes of steam pres-

sure. My turbine generator includes a generator which is directly connected to a turbine wheel, a throttle valve for controlling the supply of steam to the turbine wheel, 55 and a governor responsive to the speed of the turbine for shifting the throttle so as to control the speed of the turbine. In addition to the governor control of the throttle valve, I have provided a frictional brake, 60 which becomes effective to apply a varying brake-load to the turbine to prevent overspeeding of the turbine, if the control of the throttle through the steam throttle valve is defective in any way. 65

Referring more in detail to the drawings, I have shown my invention as applied to a steam turbine which includes a turbine frame 1, in which the shaft 2, is mounted to rotate in suitable bearings. This rotating 70 shaft element 2, is connected to the generator at one end, as indicated at 3, and to the turbine wheel, at the other end, which is indicated in dotted lines at 4. Steam is supplied through a pipe indicated at 5. This 75 steam passes through ports 6, to a valve sleeve 7, in which a valve 8, operates. This valve 8, is mounted on a valve stem 9, and a spring 10, bearing against the upper end of the valve holds the valve on the stem so that 80 the position of the valve is regulated by the position of the valve stem. The valve has suitable ports 11, formed in its outer surface, which are adapted to connect the ports 6, with the ports 12, and the ports 12, lead 85 to the steam nozzle which supplies the steam to the turbine wheel. By shifting the valve the supply of steam may be throttled more or less depending upon the position of the valve. When the valve is positioned as shown 90 in Fig. I, the ports are slightly open, while when the valve is positioned as shown in Fig. II, the steam is entirely shut off. When the valve is positioned as shown in Fig. IV, the ports are wide open and steam is permitted to flow through to the nozzle for operating the turbine wheel. 95

As a means for controlling the speed of the turbine to prevent over-speeding, I have provided a governor which is of the fly-ball type. Said governor includes a speed responsive device comprising governor weights 100

13, in the form of bell-crank levers, freely pivoted on screws 14, which, in turn are attached to the governor weight yoke member indicated at 15, in the drawings. This 5 governor weight yoke is carried upon the main rotating shaft element 2, and is secured in the working relation thereto by a screw 16, which is located in a slot 36, in the yoke, so that while the yoke necessarily rotates with the shaft, it is free to move axially thereon through a limited range. A spring 17, bears against one face of the yoke, the other end of this spring abutting against a fixed collar which carries the ball bearings 10 18. This spring normally forces the yoke 15, axially on the shaft toward the left in the drawings, until its movement is limited by contact of the screw 16, with the bottom of the slot 36, as shown in Figs. I, and II. 15 20 A governor sleeve member 19, is also mounted on the shaft 2, so as to rotate therewith, while capable of axial movement thereon. The governor weights 13, have inwardly projecting arms indicated at 20, which normally bear against the right hand end of the 25 governor sleeve 19. A spring 21, is adapted to rest against a bearing sleeve on the governor sleeve 19, and the other end of this spring 21, bears against a collar 22, fixed 30 to the shaft 2. This spring 21, normally forces the governor sleeve to the right as viewed in Fig. I, so as to press the right hand end thereof against the arms 20, of 35 governor weights. As the shaft 2, rotates and the speed becomes sufficient to move the governor weights 13, radially outward from the axis of the shaft, the governor sleeve 19, will be forced to the left by the leverage exerted through the arms 20, the spring 40 21, being compressed.

A thrust ring 23, rests against the bearing 45 24, on the left hand end of the governor sleeve. This thrust ring 23, is pivoted to a supporting yoke 26, by two oppositely located screws 25. The yoke 26, is fastened to a yoke shaft 27. This yoke shaft extends across the frame and projects through the side wall of the oil reservoir in the frame 1. On the outwardly extending end of the 50 yoke shaft is an arm 28. The endwise movement to the left imparted to the governor sleeve 19, through the ring 23, will swing the yoke, thus turning the shaft 27, and raising the arm 28. The arm 28, carries an adjustable screw 29, on its outer end which may be adjusted in the outer end of the arm and held in adjusted position by clamping screw 30. The screw 29, is adapted to be brought into engagement with the lower end of the 55 60 valve stem 9. Thus, the radial movement of the governor weights 13, corresponding with increased speed of the turbine shaft, moves the arm 28, so as to raise the outer end thereof and this raises the valve stem 65 and the valve, so as to throttle the supply

of steam and thus hold the turbine speed within safe limits. When the speed approaches an unsafe limit the arm 28, moves up to close or partially close the valve port 11, and as the speed of the turbine drops, 70 then the governor weights 13, move toward the axis of the shaft, releasing the pressure against the governor sleeve 19, and permitting the spring 21, to move the governor sleeve in the opposite direction. Thus the 75 valve means is operated to control the speed of the rotating element 2, by movement of the sleeve member 19. A spring 31, is attached at its upper end to the arm 28, and at the lower end to a screw bolt 32 and thus 80 connected between the arm 28 and the lower side of the casing 1 into which the bolt 32 is threaded, the tension of said spring being adjustably controlled by this bolt. The adjustment of the spring 31, will determine 85 the speed of the turbine, for the governor weights 13, operate against the tension of this spring, as well as against that of the spring 21, and must overcome both, in order to lift the arm 28. To permit increased 90 normal speed of the turbine the screw bolt 32, is turned in a direction to increase the tension on the spring 31, and to decrease the normal speed of the turbine, the screw bolt 32, is turned in a direction to decrease the 95 tension of this spring 31. This spring is readily accessible and may be adjusted while the turbine is running.

In case what may be called the primary governing action (*i. e.* by regulation of the 100 supply of motive medium), should fail, my invention provides for a secondary governing action to control the speed of the rotating element 2, through the application of a friction brake load.

As above noted, the governor yoke, 15, is mounted so as to slide axially on the shaft 2, and the bottom surface of the slot 36, is held against the screw 16, by a spring 17. If, for any reason, the axial movement of 110 the sleeve 19, under the stress exerted by the lever arms 20, should be arrested before the proper cutting off of the supply of motive medium is attained, then with the continuance of the abnormal rate of speed, or the 115 increase thereof, the fulcrum of the governor weight lever 20, will change from its normal position at the pivotal bearing 14, to a point indicated at *w*, in Fig. III. Thereupon the stress, due to outward radial 120 movement of the governor weights, will cause the governor yoke 15, to move axially toward the right, thus compressing the spring 17, and causing the right hand face of the yoke to engage frictionally with the 125 stationary annulus 33, which is rigidly secured to the frame 1. This friction automatically establishes a brake load, whose effective value will vary as the centrifugal force operating upon the governor weights 130

13, varies, and the speeding of the turbine will be restricted within a safe limit. Thus the loading means is operated to apply the speed-controlling load by movement of the 5 yoke member 15.

It is understood, of course, that the springs in the governing mechanism are all proportioned to act at the proper times and in the proper relation to one another.

10 The secondary, or friction brake, governing action just described is that which occurs when what may be called the normal endwise movement of the sleeve 19, to the left is not sufficient to secure the effective 15 action of the primary governing members.

In case, however, such conditions should arise that endwise movement of the sleeve 19, to the left under the action of the governor weights should not occur, or if its normal 20 endwise movement should not be attended by the above described transfer of the fulcrum of the lever 20, to the point α , my invention still provides for bringing the friction brake load into action.

25 It will be noted that an annular shoulder 37, is formed on the shaft 2, at a region adjacent to the left hand end of the sleeve 19, but at such a distance therefrom as to leave a slight interval during normal operation 30 of the sleeve 19.

Thus, when the parts are in the position shown in Fig. III, the friction brake at 15, has become effective, but the left hand extremity of the sleeve 19, has not yet moved 35 into contact with the shoulder 37, nor is the spring 21, completely compressed.

If, however, the normal endwise movement of the sleeve 19, toward the left should not result in the application of the friction 40 brake, and said movement of the sleeve continues, then the left hand end of the sleeve will bring up against the abutment afforded by the shoulder 37, which thus acts as a stop for the sleeve member 19, and since the 45 governor weights can then no longer move the sleeve to the left, their fulcrum must change to the point α , with the result that the friction brake devices will be brought into play. Thus by limiting the movement of the sleeve 50 member 19, by means of the stop shoulder 31, ultimately effective movement of the yoke member 15, is insured if the action of said sleeve member 19, proves ineffective.

While I prefer to provide this rigid abutment or stop in the form of a shoulder upon the shaft, it should be observed that by proportioning the spring 21, itself in the manner shown in the drawings, its coils will substantially close up under the compression 60 due to a similar extent of movement of the sleeve 19, toward the left, and thereupon said spring will become, in effect, a rigid collar, constituting an abutment or stop which will be effective in the same manner 65 as the abutment formed by the shoulder 37,

described above. Of course, if the compression of the spring 21, to its substantially closed condition is to be relied on to accomplish the purpose set forth, it would be unnecessary to employ the shoulder 37. In 70 either case an abutment or stop is provided and the same result is attained, but I have described and shown the construction embodying the shoulder 37, because I consider it preferable.

Having thus described a typical embodiment of my invention, I desire to point out that it is not restricted to engines operated by steam, or other elastic fluids, but is applicable to any motor device whose supply 80 of motive medium is capable of control by a movable member.

Furthermore, it is obvious that changes in the details of construction and the arrangement of the parts in the embodiment shown, 85 may be made without departing from the spirit of the invention as set forth in the appended claims.

Having thus described my invention, I claim:

1. A governor mechanism comprising, in combination, an automatic rotary speed-responsive device driven by the motor to be governed; means including a member actuated directly by said rotary speed-responsive 95 device for normally controlling the supply of motive medium to said motor; and means actuated by said rotary speed-responsive device independently of the means aforementioned to apply a friction brake load to 100 said motor under predetermined conditions.

2. A turbine governor mechanism comprising, in combination, rotary speed-responsive governor weights driven by the turbine to be governed; means including a 105 throttle valve and a member actuated directly by said weights for normally controlling the supply of motive fluid and the speed of the turbine; and means actuated by said governor weights independently of the 110 means aforementioned to apply a friction brake load to the turbine in the absence of effective control thereof by said valve.

3. A governor mechanism comprising, in combination, a rotary shaft driven by the 115 motor to be governed; a governor device on said shaft including governor weights and members separately movable by said weights; means actuated by said weights through one of said members for normally 120 controlling the supply of motive medium to said motor; and means actuated by said weights through the other of said members to apply a load to said motor in the absence of effective control thereof by said first-mentioned means.

4. A governor mechanism comprising, in combination, a rotary shaft driven by the motor to be governed; a governor device on said shaft including governor weights and 130

- members movable in opposite directions along said shaft by said weights; means actuated by said weights through one of said members for normally controlling the supply of motive medium to said motor; and means actuated by said weights through the other of said members to apply a load to said motor in the absence of effective control thereof by said first-mentioned means.
10. 5. A governor mechanism comprising, in combination, a rotating element; a governor device carried thereby including governor weights and alternative fulcrum members for said weights movable by them; and means operable by movement of either said fulcrum members for controlling the speed of said rotating element.
6. A governor mechanism comprising, in combination, a rotating shaft; a governor device carried thereby including governor weights and alternative fulcrum members for said weights movable by them axially along said shaft; means operable to control the speed of said shaft by axial movement of either of said fulcrum members by said weights as aforesaid; and means limiting such movement of one of said fulcrum members, so as to insure ultimately effective movement of the other if the action of the first proves ineffective.
7. A governor mechanism comprising, in combination, a rotating element; a governor device carried thereby including governor weights and fulcrum members for said weights movable by them; means resisting movement of one of said fulcrum members by said weights; stop means limiting movement of the other fulcrum member by said weights, so as to insure ultimate movement by them of the one affected by said resisting means; primary speed controlling means operable by initial movement of said stop limited fulcrum member to control the speed of said rotating element; and secondary speed controlling means operable by movement of the fulcrum member affected by said resisting means after said stop means becomes effective to prevent movement of the other.
8. A governor mechanism comprising, in combination, a rotating element; a governor device carried thereby including governor weights and fulcrum members for said weights movable by them; means for regulating the supply of motive medium to the motor to be governed operable by movement of one of said members and for applying a load to said motor operable by movement of the other of said members; and means for limiting movement of said first-mentioned member so as to insure movement of the other if the action of the first proves ineffective.
9. A turbine governor mechanism comprising, in combination, a shaft; a governor device on said shaft including governor weights, a yoke pivotally connected to said weights and movable by them, and a sleeve movable along said shaft by said weights; means actuated by movement of said sleeve by said weights to throttle the supply of motive fluid to the turbine; and means operated by shifting of said yoke by said weights to apply a frictional brake load to the turbine in the absence of effective control of the motive fluid by movement of said sleeve.
10. A turbine governor mechanism comprising, in combination, a shaft; a governor device on said shaft including governor weights, a yoke pivotally connected to said weights and movable along said shaft by them, and a sleeve also movable along said shaft by said weight; means controlled by movement of said sleeve for throttling the supply of motive fluid to the turbine; a spring normally holding said yoke in fixed position against the influence of said weights; and a friction member in the path of movement of said yoke by said weights for engagement therewith to apply a friction brake load to the turbine when control of its speed by movement of said sleeve proves ineffective.
11. A turbine governor mechanism comprising, in combination, a shaft; a governor device on said shaft including pivotally mounted governor weights and a sleeve movable along said shaft by said weights; a spring resisting such movement of said sleeve; a stop limiting movement of said sleeve by said weights against the action of said spring; means operated by said sleeve for controlling the supply of fluid to the turbine; and means brought into action by said governor weights to apply a friction brake load to the turbine upon arrest of said sleeve by said stop.
12. A turbine governor mechanism comprising, in combination, a shaft; a governor device on said shaft including pivotally mounted governor weights and a sleeve movable along said shaft by said weights; a compression spring opposing such movement of said sleeve substantially rigid in its resistance thereto when compressed thereby beyond a certain limit, so as to serve as a stop for the sleeve; means operated by said sleeve for controlling the supply of motive fluid to the turbine; and means operated by said weights to apply a friction brake load to the turbine when said spring becomes effective as a stop.
13. A turbine governor mechanism comprising, in combination, a shaft; a governor device on said shaft including governor weights, a yoke pivotally connected to and supporting said weights and movable along said shaft by them, and a sleeve also movable along said shaft by said weights; a spring normally opposing movement of said

sleeve as aforesaid by said weights; a valve-controlling arm operatively connected with said sleeve; a speed-regulating spring acting upon said arm and sleeve in opposition to the influence of said weights as aforesaid; means for adjusting the tension of said regulating spring; and a friction member in the path of movement of said yoke coöperating therewith to apply a friction

brake load to the turbine in the absence of effective control by said valve.

In testimony whereof I have hereunto signed my name at Philadelphia, Pennsylvania, this twenty-sixth day of March, 1918.
